UNITED STATES PATENT OFFICE.

GEORGE A. WALKER, OF OAK PARK, ILLINOIS.

WINDOW-VENTILATOR.

1,201,656.

Specification of Letters Patent.

Patented Oct. 17, 1916.

Application filed September 19, 1914. Serial No. 862,442.

To all whom it may concern:

Be it known that I, GEORGE A. WALKER, a citizen of the United States, residing at Oak Park, in the county of Cook and State 5 of Illinois, have invented certain new and useful Improvements in Window-Ventilators, of which the following is a specification.

This invention relates to a ventilating device adapted to be inserted in a window below the lower sash thereof, and the objects of the invention are to produce an efficient ventilator which may be very cheaply manufactured; which is extensible 15 and contractible to fit in windows of different widths; which may be inserted in the window in a variety of positions to suit the wishes or convenience of the user; and which permits fresh air to enter while at 20 the same time excluding or softening the light, thus making the ventilator peculiarly adapted for use in a bedroom window.

In the accompanying drawings, Figure 1 is a front view of a window in which is 25 inserted a ventilator embodying the features of my invention. Fig. 2 is a transverse vertical sectional view through the window and the ventilator. Figs. 3, 4 and 5 are horizontal sectional views illustrating the 30 different positions of the ventilator when inserted in windows of different width. Figs. 6 and 7 are also horizontal sectional views showing different positions in which the ventilator may be placed to suit the 35 wish or convenience of the user. Fig. 8 is a fragmental side elevation of a modified construction. Fig. 9 is a view, on an enlarged scale, taken in the plane of dotted line 9—9 of Fig. 8. Fig. 10 is a perspective view of a clip comprised in the modified 40 construction.

The window casing is indicated at A and the lower sash at B. In its preferred embodiment, which I have illustrated in the 45 drawings, the ventilator comprises a body, the end portions of which are secured in rigid end frames and the mid-portion of which is flexible. The body may be composed of a plurality of spaced parallel 50 wooden strips or splints 10, which may be woven together in the form of a fabric by warp cords 11. The strips 10 extend vertically and those at the end portions of the body are rigidly secured in end frames 12, 55 which in the present instance are three-

sided. The strips which are located between the adjacent ends of the end frames 12 are held in place solely by the warp cords 11.

In inserting the ventilator in a window, 60 the lower sash is raised a sufficient distance, the end frames 12 are inserted in the sash grooves of the casing A and if the window is of sufficient width, the ventilator will lie in a straight line beneath the lower 65 edge of the sash, which is pulled down to rest upon the upper edge of the ventilator. For a narrower window, the central flexible portion of the ventilator may be bowed to one side of the plane of the end frames as 70 indicated in Fig. 4. For a still narrower window, the adjacent ends of the rigid end portions of the ventilator may be overlapped more or less, with the middle flexible portion lying between them, as shown in 75 Fig. 5.

Figs. 6 and 7 indicate two further positions in which the ventilator may be placed, either bowing inwardly or outwardly from 80 the window as may please the user.

Figs. 8, 9 and 10 illustrate a modified construction wherein a clip 13 is pivoted to either or both of the upper and lower edges of the ventilator, the clip being pivoted at 85 14 to one of the end frames 12, and being of sufficient length to engage the other end frame. As shown in Fig. 9, the flexible midportion of the ventilator may be held in the plane of the ventilator by the clip 13, the splints 10 assuming an overlapped or angular position. When it is desired to place the ventilator in some such position as those shown in Figs. 6 and 7, the clip 13 may be swung out of operative position. 90

It will be seen that this ventilator may be 95 very cheaply manufactured, and that owing to the flexible central portion it may be adapted to windows that vary in width and may be placed in several different positions in a window. The ventilator is peculiarly adapted for use in bed chambers on account of the fact that it acts as a blind in excluding a portion of the light and thus gives a softened light in the room. Unlike an ordinary window shade, the ventilator permits the passage therethrough of a sufficient quantity of fresh air for ventilation purposes, while preventing a direct draft.

It is obvious that the embodiment shown in the drawings is susceptible of various 110

modifications without departing from the scope of the invention as defined by the terms of the appended claims.

I claim as my invention:

- 5 1. A ventilator comprising a pair of end frames spaced apart at their adjacent edges and a plurality of slats filling said end frames forming a flexible connection therebetween, a portion of said end frames and 10 slats being adapted to overlap each other.
- 15 2. A window ventilator comprising a pair of end frames, spaced slats rigidly secured in said frames and spaced slats flexibly connected together and joining the adjacent 15 ends of said end frames, said end frames being adapted to extend inwardly or outwardly from the plane of the window.
- 15 3. A ventilator comprising a body composed of spaced slats flexibly connected to

gether, the ventilator being adapted to be 20 inserted edgewise in a window beneath the lower sash thereof, with said slats standing substantially vertically, end frames in which the end portions of said body are rigidly secured, the adjacent ends of said frames being spaced apart and a portion of said body between said end frames forming a flexible connection between the frames, said end frames being adapted to bow inwardly or outwardly from the plane of said 30 window.

In testimony whereof, I hereunto set my hand in the presence of two witnesses.

GEORGE A. WALKER.

In the presence of—

GEORGE L. CHINDAHL,
MARGARET H. MANN.
